The ornamental design for a foldable nail file, as shown and described.

DESCRIPTION

FIG. 1 is a perspective view of the front and right side of a foldable nail file according to my design with the nail file in the closed position;

FIG. 2 is a front elevational view thereof;

FIG. 3 is a perspective view showing the design partially opened;

FIG. 4 is a perspective view showing the design completely opened;

FIG. 5 is a rear and right side perspective view of FIG. 4; and,

FIG. 6 is a rear and right side perspective view of FIGS. 1 and 2.

The surface(s) or portion(s) of the article not shown in the drawings or described in the specification form(s) no part of the claimed design.
